(57) **CLAIM**

The ornamental design for a cream and deodorant dispenser container, as shown and described.

DESCRIPTION

The present invention is related to co-pending Design applications 29/113,783, and 29/113,784, all entitled "Cream and

Deodorant Dispenser Container", filed herewith. FIG. 1 is a front elevational view of the cream and deodorant dispenser container, the back elevational view thereof being a mirror image thereto, showing my new design; FIG. 2 is a top plan view relative to FIG. 1; FIG. 3 is a front elevational view thereof relative to FIG. 1 with the cap removed for clarity of illustration, the back elevational view thereof being a mirror image thereto; FIG. 4 is a left side elevational view thereof relative to FIG. 3; FIG. 5 is a right side elevational view thereof relative to FIG. 3; FIG. 6 is a top plan view relative to FIG. 3; FIG. 7 is a right side elevational view relative to FIG. 1; FIG. 8 is a left side elevational view relative to FIG. 1; FIG. 9 is a bottom plan view relative to FIG. 1; FIG. 10 is a front elevational view for a second embodiment of the invention; FIG. 11 is a top plan view relative to FIG. 10; FIG. 12 is a front elevational view thereof relative to FIG. 10 with the cap removed for clarity of illustration; FIG. 13 is a right side elevational view thereof relative to FIG. 12; FIG. 14 is a left elevational view thereof relative to FIG. 12; FIG. 15 is a top plan view relative to FIG. 12; FIG. 16 is a right side elevational view relative to FIG. 10; FIG. 17 is a left side elevational view relative to FIG. 10; FIG. 18 is a bottom plan view relative to FIG. 10; FIG. 19 is a front elevational view for a third embodiment of the invention; FIG. 20 is a top plan view relative to FIG. 19; FIG. 21 is a front elevational view thereof relative to FIG. 19 with the cap removed for clarity of illustration; FIG. 22 is a top plan view relative to FIG. 21; FIG. 23 is a right side elevational view relative to FIG. 19; FIG. 24 is a left side elevational view relative to FIG. 19; and FIG. 25 is a bottom plan view relative to FIG. 19. FIG. 26 is a right side elevational view relative to FIG. 21; and, FIG. 27 is a left side elevational view relative to FIG. 21.
